(No Model.)

P. JAMES.
CLASP.

No. 518,956.

Patented May 1, 1894.

UNITED STATES PATENT OFFICE.

PARKER JAMES, OF VANDALIA, MICHIGAN.

CLASP.

SPECIFICATION forming part of Letters Patent No. 518,956, dated May 1, 1894.

Application filed June 7, 1893. Serial No. 476,858. (No model.)

To all whom it may concern:

Be it known that I, PARKER JAMES, a citizen of the United States of America, residing at Vandalia, in the county of Cass and State 5 of Michigan, have invented certain new and useful Improvements in Clasps, of which the following is a specification.

This invention relates to improvements in a clasp or fastening device to be secured to a 10 band, belt, or rope, for the purpose of securing bundles, packages, or articles in a compact form, and which may also be used as a bag tie.

The object of my invention is to provide a 15 clasp or securing device, simple in construction, which may be cheaply manufactured, and which may be readily and quickly operated for a variety of purposes.

For a full and complete understanding of 20 my invention, reference is to be had to the accompanying drawings in which corresponding letters indicate like parts in the several views.

Figure 1, is a perspective view of my device 25 attached to a band or belt, the same being shown in extended form. Fig. 2, is a perspective view showing the fastening device in an operative position for holding a bundle or package of suitable size. Figs. 3, 30 and 4, are sectional views, showing the engagement and manner of disengagement respectively of a hook and fastening piece. Fig. 5, represents a modified form of a fastening piece.

35 In the drawings: A represents a rectangular fastening piece of thin metal, preferably flexible, having a series of three or more rectangular apertures, a , a' , a^2 , therein, as shown. The corners of one end are cut off, see a^3 , a^3 , 40 and apertures a^4 , are provided in this end in order that the inner end of a band or belt B of flexible material may be riveted to this end of piece A or otherwise suitably secured thereto.

45 A^2 is a modified form of a fastening piece, consisting of a link chain A^3 . Band or belt B of suitable length is of such width as to permit its outer end to be readily inserted in one of the apertures, a , a' , a^2 , in piece A, 50 and the band or belt to be drawn in or out of the aperture for purposes hereinafter described. Near the outer end of band B is a metal hook C of thin material and of the

same width as the band. This hook is riveted or securely attached to the band, the 55 middle bent portion c , of the hook projecting inwardly when the band is in an operative position, see Fig. 2.

To the outside of band B near the outer end c' of hook C, is riveted or securely attached 60 one end of a short band or belt D, of a length about equal to the length of belt B from hook C to its outer end, and of the same width as B.

The operation of the device is as follows: 65 The bundle, package, or bag which is to be secured is encircled by the fastening device, the inner side of the band contacting with the same. The outer end of band B is inserted through one of the apertures in the 70 fastening piece A, depending upon the size of the article to be secured, and the band drawn through the aperture, pressing band D backwardly against the inwardly bent surface of the hook until the hook engages the 75 side of the aperture nearest the outer end of the fastening piece, see Fig. 2.

To unfasten the article so secured, all that is necessary is to pull the free end of band D 80 which lifts the hook C out of engagement with the side of the aperture with which it is engaged, and permits band B to be readily loosened and removed, see Fig. 4.

Having thus described my invention, what I claim, and desire to secure by Letters Patent, is—

1. The combination with a hook, of a series of metallic eyes attached to the hook by a flexible connection, one extremity of said connection being secured to the inner face 90 of the hook and terminating in projecting branches which are adapted respectively for drawing said eyes into and out of engagement with the hook, as specified.

2. The combination with a hook, of a series of pivotally connected links attached to the hook by an interposed flexible connection, and projecting branches of said connection secured to the inner face of the hook, as specified.

In testimony whereof I affix my signature in presence of two witnesses.

PARKER JAMES.

Witnesses:

JOEL COWGILL,

ROBERT C. SLOAN.
